UNITED STATES PATENT OFFICE.

ALBRECHT ULLI, OF LE LOCLE, SWITZERLAND.

HAT-FASTENING DEVICE.

1,393,186.

Specification of Letters Patent. Patented Oct. 11, 1921.

Application filed April 10, 1919. Serial No. 288,912.

To all whom it may concern:

Be it known that I, ALBRECHT ULLI, a citizen of the Swiss Confederation, and residing at Le Locle, Switzerland, have invented certain new and useful Improvements in Hat-Fastening Devices, of which the following is a specification.

The present invention has reference to certain new and useful improvements in devices for securing ladies' hats on the head, and relates more particularly to a vaulted, substantially bridge-shaped device to be permanently attached to the interior of the hat, comprising a stationary frame part and a comb member journaled thereon having curved teeth or tines, which comb member for engaging or releasing the wearer's hair is rotated relative to the stationary frame member in the one or the other direction by means of a headed pin inserted through the wall of the hat crown, and the invention essentially consists of the construction, arrangement and coöperation of parts as will now be described in detail in connection with the accompanying drawing, in which Figure 1 represents a side elevation of the fastening device; Fig. 2 is a cross-section on line II-II of Fig. 1; Fig. 3 is a top view of the device, and Fig. 4 a longitudinal section therethrough on a larger scale, with the middle portion broken out.

To the inside of the hat crown 1, shown in Figs. 1 and 3 in dotted outline, there are suitably secured at opposite points the inwardly converging support brackets 2 of metal or other suitable material. An oblong frame member 3 is supported between these brackets 2 by means of end slides 4 which partly encircle the bracket ends and which are provided with notches 5 (Fig. 4) with which coöperate projections or beads 6 on the brackets, for fitting the fastening device to hats of different widths and also for preventing inadvertent relative displacement of frame and brackets. The frame 3 is provided at the shorter supported ends with upwardly directed integral end walls 7 and 8 respectively. To the wall 7 is rigidly secured by means of the pins 10 one end of a doubly conoidal member 9, tapering from the extremities toward the middle and which hereinafter I will refer to simply as the cone member, while in the other wall 8 is rotatably journaled the boss 11 of the gripper or comb member. The latter is in the shape of a base portion 12 with upwardly

curving teeth 12' and is designed to rotate about the cone member 9, which latter is provided at the end facing the upstanding end wall 8 with a concentric depression 13 in which engages the head 14 of a hollow stud 15 secured in the boss 11, so that the cone member 9 is held concentric within the comb member.

The annular end wall 12'' of the comb member is clamped between the flange of the stud 15 and the boss 11, and the other annular wall 12° engages in a circumferential depression 16 in the cone member 9. The teeth 12' of the comb at their base lie close to the member 9 but toward their upper free ends are gradually extended away therefrom, as clearly shown in Fig. 2, so that the curved space between the cone and the teeth gradually tapers down toward the base of the teeth. On rotation of the comb member strands of hair caught between the cone and the teeth, obviously, will be wedged in and clamped fast; they can not escape, they prevent inadvertent rotary return movement of the comb member, and they thus securely hold the hat provided with the fastener on the head of the wearer.

In order to have all comb teeth seize a substantially equal amount of hair, without injury to the coiffure and the hair roots, the comb member and the cone are substantially in the shape of a hyperboloid, that is to say their diameters gradually correspondingly increase from the center toward the respective ends, so that their generatrices extend in the vertical plane of the longitudinal axis below the latter all over their length parallel to the curvature of the supporting bridge member and thus to the head of the wearer.

For rotating the comb member a hat pin 17 is used, which is to be inserted through the wall of the hat into the alined central bores of the stud 15 and the member 9. In the bore of the stud 15 extends the free end of a flat spring 18 whose other end is rigidly secured to the outside of the stud or nipple 15, and the pin presents a flattened portion 19 with which the leaf spring 18 cooperates in the manner of a wedge or key, so that on rotation of the pin the comb member also is rotated in the same direction.

This elastic connection between the operating pin and the operated comb member causes the hair to be caught carefully and softly.

The described operative connection be-

tween the supporting brackets and the intermediately supported frame, as also the arrangement of the stationary conoidal member and the comb member with its rotary movement directly about the cone, offer the advantage that the same fastening device may be used for variously sized hats.

What I claim is:—

1. A hat fastening device comprising a fixed cone member, a comb member having teeth curved about the periphery of said cone member and spaced therefrom, and means for rotating said comb member to rotate the teeth thereof about the periphery of the cone member.

2. In a device of the character set forth, in combination, support brackets adapted to be secured at opposite points to the inside of a hat, an oblong frame member, sleeves extending from the smaller end walls of said frame and adapted to slide on the respective free ends of said brackets, means for locking said sleeves to said brackets in different operative positions, a cone member rigidly supported in said oblong frame and having its longitudinal contour conform substantially to the respective curvature of the human head, a comb member comprising a base portion and a plurality of curved, hair engaging teeth increasing in size from the center toward the ends to respectively conform to the curvature of said cone member, said teeth at their base lying close to said cone member and their curvature lessening toward their free ends so that a hair gripping space is presented between said cone member and said comb member of gradually increasing extent, and means for rotating said comb member about said cone member in forward and backward limited direction.

3. In a device of the character set forth, in combination, support brackets adapted to be secured at opposite points to the inside of a hat, an oblong frame member, sleeves extending from the smaller end walls of said frame and designed for sliding and locking engagement with said brackets, a cone member rigidly supported in said frame and having its longitudinal contour conform substantially to the respective curvature of the human head, a comb member journaled in said oblong frame with capability of rotary movement about said cone member and comprising a base portion and a plurality of curved teeth, the latter in size respectively conforming to the curvature of said cone member, their base lying close to said cone member and their individual curvature lessening toward their free ends so that a space is left between said cone member and said comb member of gradually increasing extent, said cone member and said comb member having alined axial bores, and means for rotating said comb member about said cone member in forward and backward direction from without the hat, comprising a headed pin, a longitudinally extending flattened portion or key way thereon, said pin designed to be inserted through the hat crown into and through said alined bores of said cone member and said comb member, an axially bored member journaled in the one narrow end wall of said oblong supporting frame and rigidly secured to said comb member, and key means in connection with said axially bored member adapted to coact with said flattened portion of said headed pin, the parts being constructed, arranged and coöperating substantially as shown and set forth.

ALBRECHT ULLI.
